WALL COPING

George M. Schaulin, Akron, Ohio, assignor to
 The Robinson Clay Product Company, Akron,
 Ohio, a corporation of Maine

Application January 11, 1941, Serial No. 374,099

6 Claims. (Cl. 72—86)

This invention relates to wall coping such as commonly is used upon the upper course of a masonry structure, and more especially it relates to wall coping that consists of clay or tile sections positionable in end-to-end relation and having end formations that interfit with adjacent sections.

The invention is an improvement upon my prior U. S. Patent No. 1,972,819, issued September 4, 1934. The coping constituting the subject matter of the aforesaid patent consisted of tile sections, each of which sections comprised a longitudinally extending tongue projecting from one end thereof adapted to be inserted beneath the top wall of an adjacent section, and formed on its under side with two parallel, depending, undercut ribs adapted to rest upon the top of a wall and mechanically to interlock with a mortar course upon said wall. The arrangement was satisfactory in cases where the coping was low, that is, positioned close to the top of a wall, but when a taller coping was desired, the provision of taller undercut ribs on the coping sections presented manufacturing difficulties, such as the prevention of breakage of the ribs during the forming and firing of the tiles. It is to the relief of this condition that this invention is directed.

The chief object of the present invention, therefore, is to provide an improved sectional wall coping of the character mentioned. More specifically, the invention aims to provide coping units of greater height than shown in the aforementioned patent and which interlock with the mortar course on top of a wall, yet which do not require longitudinal supporting ribs of increased height for achieving this purpose. Another object is to provide an improved wall coping of the character mentioned wherein the supporting elements of the coping are subject to less breakage during manufacture. Other objects will be manifest as the specification proceeds.

Of the accompanying drawing:

Figure 1 is a plan view of a wall coping embodying the invention, a part thereof being broken away and in section;

Figure 2 is a side elevation thereof, a part being broken away and in section;

Figure 3 is a fragmentary perspective view of one end portion of a coping section;

Figure 4 is an end elevation of the opposite end of the coping section shown in Fig. 3;

Figure 5 is a section on the line 5—5 of Fig. 2; and

Figure 6 is a section on the line 6—6 of Fig. 2. Referring to the drawing, there is shown a wall

5 coping comprising a succession of units or sections 10, 10 that are mounted atop of a wall 11, the latter being shown, for illustrative purposes, as a brick wall. Each section 10 is composed of tile or baked clay of suitable or desired thickness for economical and effective firing, and preferably is of concavo-convex form in transverse section. Opposite lateral margins of the section are provided with integral depending skirts or side walls 12, 12 adapted to overlap the joint between the coping and the wall upon which it is mounted.

10 For interlocking each coping section 10 with the mortar course on the top of wall 11, the confronting faces of the skirt portions 12 are formed with respective laterally inwardly projecting, longitudinally extending ribs 14, which ribs have a flat bottom face disposed somewhat above the lower, free margins of the skirts 12. At the bottom of each rib 14 there is a longitudinally extending undercut recess 15 disposed between the rib and adjacent skirt, the arrangement being such that mortar 16 between the coping section and the wall 11 will flow into said recesses 15, as shown in Figures 5 and 6, and thus interlock 15 the section with said mortar course. At one end 20 of the coping section the ribs 14 terminate inwardly of the end thereof, as shown in Figs. 1 and 2, and at the opposite end of the section they project beyond the end thereof and are integral 25 with a tongue structure presently to be described. Preferably the skirts 12 are somewhat thinner below the ribs 14 than above them, as is clearly 30 shown in Figures 3 to 6 of the drawing.

35 Each section 10 has at one end thereof a portion 18 extending inwardly or downwardly of the concave or under side thereof, and inwardly and laterally of the skirt portions 12 thereof, said portion 18 being formed with a projecting tongue 19 that extends beyond the end of the coping. Said tongue is arcuate in its medial region and concentric with the arcuate top of the coping, the ends of said arcuate medial region connecting with vertically disposed portions 19a, 19a that are substantially parallel to the 40 skirt portions 12. At their lower ends the respective vertical portions 19a of the tongue merge with the projecting end portions of the ribs 14, as is best shown in Fig. 3. The convex face of the medial portion of the tongue 19 is disposed somewhat inwardly of the concave bottom face of the medial portion of the coping section, and the distance between the outer lateral faces of the vertical tongue portions 19a is less than the distance between the inner faces of 45 the skirts 12. The arrangement is such that 50

the tongue 19 is able to extend beneath the complementally shaped top of the confronting end portion of an adjacent coping section, and between the skirt portions 12 thereof, the end portion of the adjacent section thus constituting a socket for said tongue and the skirts of adjoining sections being in end-to-end abutment.

The improved coping sections are readily and effectively joined to provide an improved joint that prevents moisture from finding its way therethrough and into the wall structure 11. Cement or mortar is applied on top of the tongue 19 of a previously positioned coping section and to the outer faces of vertical portions 19a of the tongue. Then upon application of a succeeding coping section to the wall, the mortar is squeezed between the coping members and into the joint between the confronting end faces of the sections including the skirts 12 thereof.

Modification may be resorted to without departing from the spirit of the invention or the scope thereof as defined by the appended claims.

What is claimed is:

1. A coping unit comprising a body portion that is substantially longitudinally flat and having longitudinally extending skirt portions co-extensive with its lateral margins and depending therefrom, and laterally projecting supporting ribs formed on the confronting faces of said skirt portions intermediate the upper and lower limits thereof, each rib having a downwardly extending end portion which is spaced from the skirt on which it is formed.

2. A coping unit comprising a body portion that is substantially longitudinally flat and having longitudinally extending skirt portions co-extensive with its lateral margins and depending therefrom, and laterally projecting supporting ribs formed on the confronting faces of said skirt portions intermediate the upper and lower limits thereof with the bottom face of each rib disposed above the bottom margin of the adjacent skirt portion, each rib being so shaped as to

define an undercut recess between the lower portion thereof and the adjacent skirt.

3. A coping unit comprising a body portion that is substantially longitudinally flat and having longitudinally extending skirt portions co-extensive with its lateral margins and depending therefrom, and laterally projecting supporting ribs formed on the confronting faces of said skirt portions intermediate the upper and lower limits of the latter, said ribs terminating short of one end of said skirts and projecting beyond the opposite end of said skirts.

4. A coping unit comprising a body portion that is substantially longitudinally flat and having longitudinally extending skirt portions co-extensive with its lateral margins and depending therefrom, and laterally projecting supporting ribs formed locally on the confronting faces of said skirt portions, said ribs terminating short of one end of said skirts and projecting beyond the opposite end thereof, each rib being so shaped as to define a downwardly opening undercut recess between itself and the skirt on which it is formed.

5. A coping unit comprising a body portion that is substantially longitudinally flat and having longitudinally extending skirt portions co-extensive with its lateral margins and depending therefrom, a projecting wall at one end of said structure extending inwardly from said body portion and skirts, a tongue on the inner end of said wall projecting beyond the adjacent end of the structure, said tongue being disposed below said body portion and inwardly of the skirts thereon, and laterally projecting supporting ribs formed on the confronting faces of the skirt portions and extending longitudinally thereof, said ribs merging with the tongue-supporting wall at one end of the unit.

6. A combination as defined in claim 5 including an undercut recess formed between each rib and skirt on which it is formed.

GEORGE M. SCHAULIN.
